Primary Examiner — Sandra Snapp(57) **CLAIM**

The ornamental design for a volatile dispenser, as shown and described.

DESCRIPTION

FIG. 1 is a left, top, frontal perspective view of a volatile dispenser embodying our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.

The broken line representations in the views are for illustrative purposes only and form no part of the claimed design. Dash-dot broken lines represent the boundary between claimed and unclaimed areas and form no part of the claimed design.

In a preferred embodiment the nature of this product is an air treatment dispenser suitable to hang on a person's belt, pocket, or other clothing item and dispense insect repellents (for example, mosquito repellent).
